UNITED STATES PATENT OFFICE

GROSVENOR N. ALLEN, OF ONEIDA, NEW YORK, ASSIGNOR TO ONEIDA COMMUNITY, LIMITED, OF ONEIDA, NEW YORK, A CORPORATION OF NEW YORK

DESIGN FOR A POT OR SIMILAR ARTICLE

Application filed August 1, 1929. Serial No. 32,264. Term of patent 14 years.

To all whom it may concern:

Be it known that I, GROSVENOR N. ALLEN, a citizen of the United States, residing at Oneida, county of Madison, State of New York, have invented a new, original, and ornamental Design for a Pot or Similar Article, fully described and represented in the following specification, and the accompanying drawing forming a part of the same, which is a perspective view of the pot showing my new design, the essential feature of which is the decoration on both sides of the body of the pot or similar article.

I claim:

The ornamental design for a pot or similar article as shown and described.

In testimony whereof I have hereunto set my hand.

GROSVENOR N. ALLEN.
